A. H. CRANKSHAW

PAPER BOX

Filed May 21, 1927

UNITED STATES PATENT OFFICE.

ALFRED H. CRANKSHAW, OF LYNDHURST, NEW JERSEY, ASSIGNOR TO OWENS MANUFACTURING CO., OF HOBOKEN, NEW JERSEY, A CORPORATION OF NEW JERSEY.

PAPER BOX.

Application filed May 21, 1927. Serial No. 193,206.

This invention is an improvement in paper boxes, and more particularly in that type of box designed to hold made-up articles of fabric material, such as shirts, underwear, and the like, wherein holding tapes are used to hold the articles in place.

Such boxes are usually composed of box parts, each including a body and side and end flanges. The parts are formed from blanks, which are cut or otherwise formed from suitable material, and each blank is scored or creased to indicate the boundary between flap and body, and to facilitate bending of the flaps with respect to the body in the formation of the box.

The flaps are bent at right angles to the body and suitably secured in place, as for instance by a strip of paper engaging the sides and ends of the box, and turned in at the top and bottom. A covering sheet is then applied to the bottom, completing the covering of the box. The boxes are also covered by a single sheet of paper, wrapped about the box, with the edges turned in upon the inner faces of the flaps.

The tapes which are of fabric material of suitable dimensions are usually connected to the boxes by passing the ends of the tape through slits in the bottom, prior to the application of the bottom covering or label. With this arrangement a considerable length of each tape is outside the box, between the bottom and the covering paper. The arrangement provides for an unsightly protuberance on the bottom at each tape, and should the tape be twisted or in any other condition than flat upon the bottom, the finished box would be defective.

One of the primary objects of the present invention is the provision of a box or box part, wherein tie tapes or ribbons are connected with the box in such manner as to present a minimum amount of tape outside of the box, while at the same time the tape is firmly anchored to the box.

Another object is the provision of an arrangement of tape such that the small amount of the tape outside the box is so situated with respect to the box that the protuberance in the covering paper caused by such part is least noticeable.

With these and other objects in view the invention consists in the construction and novel combination of parts fully described

hereinafter, illustrated in the accompanying drawings, and pointed out in the claims appended hereto, it being understood that various changes in the form, proportion, size and minor details of construction within the scope of the claims, may be resorted to without departing from the spirit of the invention.

In the drawings:

Fig. 1 is a bottom plan view of a box blank made in accordance with the invention.

Fig. 2 is a top plan view showing the first step in the operation of inserting the tape or ribbon.

Fig. 3 is a perspective view of the completed box looking from above.

Fig. 4 is a section on the line 4—4 of Fig. 3.

Fig. 5 is a perspective view looking from below of that part of the corner of the box provided with the tab.

In the embodiment of the invention shown, the improved box is formed in the usual manner, from a blank comprising a bottom 1, side flaps 2, and end flaps 3. These blanks are cut or otherwise formed from stock, the blank being in effect a rectangular piece of material with the corners notched as shown. The box is creased or scored on lines 4 and 5 connecting the notched corners, the scored lines indicating the boundaries between the flaps and the body.

In completing the box, the side and end flaps are turned up at right angles to the body, as indicated in Fig. 3, and held in any suitable manner. If desired, a cover flap or sheet such as is indicated at 8 may be inserted at the top of the box. This flap or sheet is of suitable material, having one edge secured to a side flap of the box near the top, as indicated at 9, the arrangement being such that the flap may be turned into the box over the goods, or outwardly to enable access to the goods.

In boxes of this character it is usual to provide holding tapes or ribbons for the goods. The tapes or ribbons are extended transversely of the box and the ends are adapted to be tied over the goods to hold them neatly in place. As previously pointed out, the tapes have heretofore been held in place by passing the ends thereof through slits in the bottom, the body of the tape being beneath the bottom, with the ends

in the box. This arrangement provides for an unsightly box bottom, and requires care in the placing of the tape to prevent twisting or folds.

5 In the present invention, the tapes indicated at 10, of which there may be one or more, are held in place by tabs struck up from the material of the box. These tabs may be struck up at any desired point in 10 the bottom, or even in the side flaps near the bottom. They are arranged in pairs transversely of the box, and being formed at the same time that the blank is cut or stamped, the formation of the tabs does not 15 in any manner increase the cost of the box.

While as previously stated the tabs may be struck up from any desired point of the box, they are preferably struck up at the corners, and in such manner that each tab 20 includes a part of the side wall or flap of the box, and a part of the bottom. As shown in the preferred position, each tab comprises a portion 11 from material of the body, and a portion 12 from the material 25 of the side flap. The tabs are formed when the blank is cut and scored, by cutting through the material on arc shaped lines, the tabs being bent along the lines connecting the ends of the arc, the said line forming 30 a hinge for the tab.

In the present instance a single pair of tabs is shown, arranged at about the transverse center of the box, but it is obvious that a pair might be arranged near each end of 35 the box if desired, thus to provide the box with two tapes. The score line or crease outlining the side flaps on the bottom of the box defines the two portions 11 and 12 of each tab, and provides a bending line, so 40 that the tabs do not interfere with the bending up of the side flaps.

In making up the boxes from the blanks, the tabs are lifted in any suitable manner to substantially the position in Fig. 2. The 45 tape 10 is then inserted beneath the tabs as shown in Fig. 2, and they are pushed back into place, carrying with them a part of the tape. The sides and ends are now folded, and the box is wrapped. The folding of the 50 side flaps bends the tabs along the line 13 dividing the portions 11 and 12, and this bend or angle between the portions 11 and 12 forms a lock to prevent displacement of the tabs into the box.

55 With tabs arranged in the preferred position, the portions of the tape outside the box are less noticeable, and no handling to which the box would be subjected in the usual course could displace the tabs. Only 60 unusual and exceptional stress, such as would work great injury to the box could displace the tabs in either direction. They are held by the tape and also by the bend or angular formation against displacement. The tapes 65 may be held in place by means of adhesive

applied to the underface of the tabs or the wrapper may be relied upon to hold them in place. The wrappers are usually gummed throughout their extent, and the adhesive on the wrapper secures the tape thereto and 70 to the box.

What is claimed as new is:

1. A box part blank including a body and side and end flaps, and having integral holding tabs formed from material of the box and 75 connected thereto along a straight line to facilitate bending of the tabs laterally from the plane of the material, said tabs being arranged in pairs transversely of the box, and the tape or ribbon being held beneath 80 the tabs with the tabs in the plane of the blank.

2. A box part blank including a body and side and end flaps, and having integral holding tabs for a tape or ribbon, said tabs being formed partly from the body of the part and partly from an adjacent flap whereby 85 to assume an angular formation when the blank is bent to shape.

3. A box part blank including a body and side and end flaps, and having integral holding tabs for a tape or ribbon, said tabs being formed partly from the body of the part and partly from an adjacent flap whereby to assume an angular formation when the blank 95 is bent to shape, said tab being unequally divided between the bottom and the flap.

4. A box part blank including a body and side and end flaps, and having integral holding tabs for a tape or ribbon, said tabs being 100 formed partly from the body of the part and partly from an adjacent flap whereby to assume an angular formation when the blank is bent to shape, said tab being unequally divided between the bottom and the 105 flap, and with the greater part thereof from the material of the flap.

5. A box part blank, including a body and side and end flaps, said blank having integral holding tabs for a tape or ribbon, 110 and being creased or scored between the flaps and the body, each tab being formed partly from the body and partly from an adjacent flap and lying upon both sides of the score or crease, whereby to assume an angular formation 115 when the blank is bent to shape.

6. A box part having a tab for connecting a tape or ribbon thereto, said tab struck up from the material of the box, and adapted to lie in the plane of the box when the ribbon is in place. 120

7. A box part having struck up tabs in the corners thereof, said tabs arranged in pairs, with the members in alignment transverse to the box, said tabs each having a 125 part thereof from the material of the box side and a part from the material of the box bottom, and a tape held beneath the tabs.

8. A box part having struck up tabs in 130

- the corners thereof, said tabs arranged in pairs, with the members in alinement transverse to the box, said tabs each having a part thereof from the material of the box 5 side and a part from the material of the box bottom, and a tape held beneath the tabs, said tabs normally in the plane of the sides and bottom.
9. A box part having a tab for connecting 10 a tape or ribbon thereto, said tab struck up from the material of the box at the angle between the bottom and a side wall thereof.
10. A box part having a tab for connecting 15 a tape or ribbon thereto, said tab struck up from the material of the box at the angle between the bottom and a side wall thereof, said tab having a part thereof from the material of the side wall and a part from the material of the bottom.
- 20 11. A box part having a tab for connecting a tape or ribbon thereto, said tab struck up from the material of the box at the angle between the bottom and a side wall thereof, said tab having a part thereof from the

material of the side wall and a part from 25 the material of the bottom.

12. A box part having a tab for connecting a tape or ribbon thereto, said tab struck up from the material of the box at the angle between the bottom and a side wall thereof, 30 said tab having a part thereof from the material of the side wall and a part from the material of the bottom, said parts of unequal size, the larger from the side wall, and a tape held beneath the tab. 35

13. A box part blank including a body and side and end flaps, and having a plurality of holding tabs for a tape or ribbon, formed by severing the material along a curved line, the ends of the line of severance spaced apart to provide a straight line hinge connection, the hinge connections between the tabs being in alinement. 40

Signed at New York city in the county of New York and State of New York this 45 18th day of May A. D. 1927.

ALFRED H. CRANKSHAW.
